UNITED STATES PATENT OFFICE.

EDWARD C. ALBREE, OF SWAMPSMOTT, MASSACHUSETTS.

CARD-INDEX.

No. 821,602.

Specification of Letters Patent.

Patented May 29, 1906.

Application filed August 22, 1905. Serial No. 275,241.

To all whom it may concern:

Be it known that I, EDWARD C. ALBREE, a citizen of the United States, residing at Swampscott, county of Essex, State of Massachusetts, have invented a certain new and useful Improvement in Card-Indexes, of which the following is a specification, reference being had therein to the accompanying drawings.

10 Large card-indexes, such as are used in connection with bookkeeping or cost-accounting systems of large manufactures, are frequently separated into a number of subdivisions, each of which is kept in a separate 15 drawer or division thereof. In such systems great care is required in placing the cards in their proper places to insure that the cards are not misplaced, as the value of the system is likely to be seriously injured if 20 cards are not put in their proper places.

My invention has for its object to provide a card-index of such construction that the user may be readily assured that each card is in its own place, but which shall not require 25 any cumbrous or expensive mechanism whatsoever to be used in connection with the card-drawer.

While I have designed my device with especial view to its use in connection with cost-30 accounting and mercantile systems, it is equally applicable to any card system where there are subdivisions in which there are considerable numbers of cards. Cards embodying my invention may be used and the 35 full benefit of the invention obtained with card-drawers of ordinary construction.

The invention will be fully understood by reference to the accompanying drawings, taken in connection with the specification, 40 the novel features thereof being pointed out and fully described in the claims at the close of this specification.

In the drawings, Figure 1 is a perspective view of a drawer containing an index embodying my invention. Fig. 2, Fig. 3, and Fig. 4 are plan views of cards for use in an index similar to the one shown in Fig. 1.

Referring now to the drawings, at A, I have indicated a card for use in the index shown in 50 Fig. 1. Along the upper edge of the card and parallel with it I place two rows B and C of characters, located in two rows of uniform spaces D. At each end of the two rows of uniform spaces D blank spaces are left for 55 convenience in indexing or in order that the corners of the cards may be cut off or pecu-

liarly shaped or cut away, as is common in connection with card-indexes of this character. In the uniform spaces D and beginning at the left-hand end, as shown in Fig. 2, I place 60 the characters "1, 2, 3, 4," &c., to represent "tens" and number as many of the spaces in this way as is necessary for the particular class of work to which the index is to be applied. If desired, the word "Tens" may be 65 placed in the space next before that containing the numeral "1." In the card shown in Fig. 2 I have given four of these spaces numerals, that card being adapted for use in a classification in which there are forty-nine 70 subdivisions. After the fourth space D a space F is left, which may be blank or may have the word "Units" printed therein, as desired. In the next ten uniform spaces E are placed the digits "1, 2, 3, 4, 5, 6, 7, 8, 9," and 75 "0." Each of the two rows B and C are provided with numerals in the same manner, the second row being intended to make it easy for a person using the index to read the number of the card, although the numeral in 80 the upper row has been obliterated by punching.

In practice each of the subdivisions is designated by a number—as, for instance, where the system is used in a factory the foundry 85 may be "25" and the finishing department "36," &c. All of the cards issued to any one department are punched in the spaces the numerals of which correspond to the number of the subdivision. If more convenient, the 90 cards may be punched before leaving the department, when they are returned to the main office. Where the latter method is employed and there are a number of persons whose duty it is to punch these cards, the several 95 persons may be provided with punches which make characteristic marks. Two of such marks are shown in Figs. 3 and 4 at H and J, respectively. By this means it is easy to determine the person who punched the card. 100

When the various cards belonging to a subdivision are placed in their card-drawers K, as seen in Fig. 1, the punch marks or notches G register with each other and form a groove as one looks across the top of the series of cards in the drawer. Should a card belonging to another subdivision be placed in the drawer, its notches will not register with the notches of the other cards in the drawer, and the fact that a wrong card is in 105 the drawer will be immediately apparent, as the view along the series of notches will be 110

obstructed. In Fig. 1 I have shown a misplaced card L. The portion of the card which extends across the groove formed by the notches in the other cards forms a visual indicator which calls attention to the misplaced card.

In Fig. 3 I have shown a card provided with five tens-figures for use with a larger number of subdivisions or departments, and in the card shown in Fig. 4 I have shown the tens-figures replaced by letters of the alphabet, as is sometimes done.

What I claim is—

1. The improved card-index system which comprises cards in subdivisions, the cards in each subdivision being provided with notches on a portion of the card which is visible when the cards are in place, the notches on all the cards in a subdivision registering with each other but the notches in no two subdivisions being alike, whereby a visual indicator of a misplaced card is formed.

2. The improved card-index system which comprises cards in subdivisions, said cards being divided into spaces along the top and provided with symbols in the said spaces, all the cards in a subdivision being provided

with registering notches corresponding to one or more of the said spaces, but the notches in no two subdivisions being alike, whereby 30 attention is called to a misplaced card.

3. The improved card-index system which comprises cards in subdivisions provided with spaces across the top and having symbols therein, one or more spaces being punched 35 out to indicate the subdivision to which the card belongs and all the cards in a subdivision being punched alike and being unlike the cards in any other subdivision.

4. The improved card-index system which 40 comprises cards in subdivisions provided with spaces across the top numbered for "tens" and "units," one or more spaces being punched out to indicate the number of the subdivision, all the cards in a subdivision 45 being punched alike and being unlike the cards in any other subdivision.

In testimony whereof I affix my signature in presence of two witnesses.

EDWARD C. ALBREE.
